(57) **CLAIM**

The ornamental design for a carrier for containers, as shown and described.

DESCRIPTION

FIG. 1 is a perspective view of a carrier for containers showing my new design.

FIG. 2 is a left elevation view of the carrier for containers of FIG. 1, the right elevation view is a mirror image.

FIG. 3 is a front elevation view of the carrier for containers of FIG. 1.

FIG. 4 is a rear elevation view of the carrier for containers of FIG. 1.

FIG. 5 is a top plan view of the carrier for containers of FIG. 1.

FIG. 6 is a bottom plan view of the carrier for containers of FIG. 1; and,

FIG. 7 is a plan view of the carrier for containers of FIG. 1 shown in an unfolded configuration.

The evenly-spaced broken lines illustrating containers depict environmental structure and forms no part of the claimed design. All other evenly-spaced broken lines depict portions of the carrier for containers and forms no part of the claimed design. The portions of the carrier for containers shown in dash-dot-dash lines indicate boundaries of the claimed design and form no part of the claimed design.
